C. M. TANSILL

SPARK PLUG

Filed July 23, 1926

Fig. 6.

Charles M. Tansill,

INVENTOR

BY *Victor J. Evans*

ATTORNEY

UNITED STATES PATENT OFFICE.

CHARLES M. TANSILL, OF WOODLAWN, MARYLAND, ASSIGNOR OF ONE-THIRD TO CHARLES E. NOLTE AND ONE-THIRD TO WALTER E. WINDSOR, BOTH OF BALTIMORE, MARYLAND.

SPARK PLUG.

Application filed July 23, 1926. Serial No. 124,482.

This invention relates to spark plugs and its primary object is to provide a spark plug which includes means for admitting air to be heated within the plug so that the heated air can be introduced in the cylinder with which the plug is associated, and thereby reduce the consumption of fuel.

A further object of the invention is to provide a manually operated means for controlling and regulating the admission of air to a plurality of spark plugs equipped with air admitting means.

Another object of the invention is to provide a spark plug which includes an intensifier for providing a maximum spark for said plug.

A still further object is to provide a spark plug having a heat proof glass core formed in part with a sleeve to house the working parts of said plug and so that they may be observed.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a longitudinal sectional view taken through the spark plug forming the subject matter of the present invention and illustrating the means for controlling the admission of air passing through the plug, arranged to allow the maximum amount of air to pass therethrough.

Figure 2 is a fragmentary view illustrating the air regulating means arranged to allow a minimum amount of air to pass through the plug.

Figure 3 is a top plan view of Figure 1.

Figure 4 is a fragmentary perspective view of the central electrode of the plug.

Figure 5 is a perspective view of the regulator for the valve which controls the admission of air through the plug.

Figure 6 is a top plan view showing my novel plugs arranged in operative position in a four cylinder engine with the means

for controlling the air to the plugs arranged for operation in unison. 55

Referring to the drawings in detail the numeral 1 indicates a shell for the plug which forms the subject matter of the present invention and which is reduced and threaded as at 2 so as to be secured in the 60 usual spark plug opening of an engine.

The core 4 is held associated within the shell through the instrumentality of the usual binding nut 5 and gaskets 6 provide a leak proof connection between the shell, 65 body of the core and the binding nut.

The core is formed from Pyrex or other similar material and includes a housing 7 rising from the body of the core 4 and centrally arranged within said housing and disposed in parallelism therewith is a sleeve 8 through which passes the main electrode 9 for slidable movement therein. The main electrode is threaded for a portion of its length and threadedly secured thereto is a 70 flat elongated strip 3 having right-angle disposed upturned ends. The strip 3 is secured in adjusted position upon the main electrode 9 by a lock nut as clearly shown in Figure 1 of the drawings, and it will be 75 apparent that the said strip can be expeditiously and adequately adjusted vertically upon said electrode 9 to position the upturned ends with respect to the shell so as to provide perfect spark gaps upon diametrically opposite sides of the lower edge of the shell. 80

The body 4 has formed in its lower end a recess 10 which is provided with a conical shaped portion communicating with a bore 90 through which passes the main electrode 9 and a lining 11 is arranged in said bore and the conical shaped portion of the recess which provides a seat for the valve 12 which is threadedly secured to said main electrode 95 at the juncture of the reduced portion 13 formed thereon. Inclined openings 14 are formed in the core and sleeve 8 respectively, at the juncture thereof with the core and these openings provide for the ingress of air 100 to the valve chamber and thence to the cylinder as will be readily apparent.

A cap 15 is provided for the top of the housing 7 and said cap is formed with an annular recess to accommodate the upper 105 edge of said housing as best shown in Fig.

ure 1 of the drawings. The cap is further provided with a centrally disposed opening to accommodate the passage of the central electrode 9 and a plurality of openings 16 surrounding said central opening to allow air to be introduced in the housing.

The means for heating the air includes a coil 17 surrounding the sleeve 8 and has its upper end secured to a terminal bolt 18 while its lower end is fixed in the core as clearly shown in Figure 1 of the drawings. The terminal bolt is provided with the usual binding nut for securing a conduit thereto from a suitable source of current. Approximately disposed opposite the terminal bolt 18 is an intensifier 19 arranged in spaced relation to the main electrode so as to provide maximum spark between the central electrode and the ground electrodes 3.

20 The movement of the central electrode is controlled by a cam regulator 20 which effects the tension of a coil spring 21 surrounding the upper end of the central electrode and which has its end convolutions engaging the innermost of the adjusting nuts 22 and a washer 23. The regulator is formed with a pair of flat surfaces 24 and 25 and an inclined surface 26 and it will be obvious that when the regulator is moved so that the washer 23 engages the surfaces 25, the spring 21 is put under its greatest compression and therefore the movement of the central electrode is restricted so as to reduce the quantity of air passing between the valve 12 and its seat, but when the regulator is moved in the position as illustrated in Figure 1, the electrode 9 is allowed its fullest movement with the result the maximum quantity of air is passed through the spark plug.

40 As shown in Figure 6, the regulator for the admission of air passing through the spark plugs are moved in unison through the instrumentality of a rod 27 and each of the regulators are provided with a bored member 28 through which the rod passes and is held therein by a screw 29. While only a four cylinder engine is suggested in Figure 6 of the drawings, it will be obvious that the rod can be associated with six spark plugs or eight, it depending upon the number of cylinders employed in the engine.

From the above description and disclosure of the drawings, it will be obvious that the spark plug which forms the subject matter of the present invention not only admits air to the cylinders on the intake stroke of the pistons thereof, but the air is heated by the coil 17 and the amount of air passing through the plug is controlled by the regulator 20 which controls the compression of the spring 21 in the manner as suggested in Figures 1 and 2. It is obvious that when the engine is laboring, it is desirable to cut down on the supply of air passing through the spark plug, but when the engine is ac-

celerating a quantity of air passing through the plug may be increased and thereby materially economize on the consumption of fuel. Again, the intensifier provides maximum sparking qualities for the electrodes, and therefore cooperates in the reduction of fuel consumption. By employing the Pyrex core and housing, the operation of the respective parts may be readily observed and therefore it may be ascertained whether or not the plug is working properly to perform its intended function.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

1. A spark plug of the character described comprising a shell, a core including a housing and secured therein, a sleeve included in said core and rising therefrom, an electrode mounted for movement in said sleeve, core and shell, a cap for said housing and being provided with openings for admitting air within said housing, means carried by said electrode for controlling the air passing through said core, compression means for said last mentioned means and including a coil spring surrounding said electrode, adjusting means for said spring and receiving one of the end convolutions thereof, a washer receiving the opposite end convolution thereof, cam means movable on said electrode and engageable with said washer for changing the compression of said spring for regulating movement of said electrode, whereby the air controlling means is regulated accordingly.

2. A spark plug of the character described comprising a transparent core, a housing included in said core, means for admitting air in said housing, a sleeve included in said housing, and means for heating said air and including an electrical coil surrounding the sleeve, a terminal receiving one end of said electrical coil, and the opposite end being grounded.

3. A spark plug of the character described comprising a shell, a core including a housing and secured in said shell, a movable electrode passing through said housing, a spring surrounding said electrode and holding the same under tension, a cap for said housing and being provided with openings for admitting air into said housing, said core being provided with air receiving openings, a valve carried by said central electrode for controlling the passage of air through said core, means for regulating the movement of said valve through the medium of said electrode and including a cam mem-

- ber mounted for movement in a manner to adjust the compression of said spring, and means secured to the lower portion of the electrode to provide spark gaps.
5. A spark plug of the character described comprising a shell, a core including a housing and a sleeve disposed within said housing, a cap for said housing, a central electrode mounted for slidable movement through said cap, sleeve, core and shell respectively, spring means for controlling the movement of said central electrode, means for regulating the compression of said spring and including a cam member mounted on said electrode for slidable movement between said cap and spring means respectively, valve means carried by said central electrode for controlling the passage of air through the core, and adjustable means car-
- ried by said electrode to provide spark gaps 20 upon opposite sides of the lower edge of the shell.
5. The combination with a plurality of spark plugs having spring pressed air admitting means therefor, of a regulator for 25 each spark plug for controlling the air passing therethrough and including a cam member having a flat surface and inclined cam surfaces, said cam surfaces being arranged in different planes and upon opposite sides 30 of said flat surface and being adapted for adjusting the compression of the spring for the admitting means, and means for operating the regulators of each spark plug in unison. 35

In testimony whereof I affix my signature.

CHARLES M. TANSILL.
